An ornamental design for a gripping device for an avionics display, as shown and described.

DESCRIPTION

Referring to the Figures, wherein:

FIG. 1 is a front view of a first embodiment of a gripping device for an avionics display disposed within a cockpit of an aircraft;

FIG. 2 is a perspective view of the gripping device of FIG. 1.

FIG. 3 is a rear elevational view of the gripping device of FIG. 2.

FIG. 4 is a front elevational view of the gripping device of FIG. 2.

FIG. 5 is a right side elevational view of the gripping device of FIG. 2.

FIG. 6 is a left side elevational view of the gripping device of FIG. 2.

FIG. 7 is a bottom plan view of the gripping device of FIG. 2.

FIG. 8 is a top plan view of the gripping device of FIG. 2.

FIG. 9 is a perspective view of a second embodiment of a

gripping device for an avionics display.

FIG. 10 is a rear elevational view of the gripping device of FIG. 9.

FIG. 11 is a front elevational view of the gripping device of FIG. 9.

FIG. 12 is a right side elevational view of the gripping device of FIG. 9.

FIG. 13 is a left side elevational view of the gripping device of FIG. 9.

FIG. 14 is a bottom plan view of the gripping device of FIG. 9.

FIG. 15 is a top plan view of the gripping device of FIG. 9.

FIG. 16 is a perspective view of a third embodiment of a

gripping device for an avionics display.

FIG. 17 is a rear elevational view of the gripping device of FIG. 16.

FIG. 18 is a front elevational view of the gripping device of FIG. 16.

FIG. 19 is a right side elevational view of the gripping device of FIG. 16.

FIG. 20 is a left side elevational view of the gripping device of FIG. 16.

(Continued)

- FIG. 21 is a bottom plan view of the gripping device of FIG. 16.
- FIG. 22 is a top plan view of the gripping device of FIG. 16.
- FIG. 23 is a perspective view of a fourth embodiment of a gripping device for an avionics display.
- FIG. 24 is a rear elevational view of the gripping device of FIG. 23.
- FIG. 25 is a front elevational view of the gripping device of FIG. 23.
- FIG. 26 is a right side elevational view of the gripping device of FIG. 23.
- FIG. 27 is a left side elevational view of the gripping device of FIG. 23.
- FIG. 28 is a bottom plan view of the gripping device of FIG. 23.
- FIG. 29 is a top plan view of the gripping device of FIG. 23. The broken lines (shown as dash-dash-dash lines) are shown in the drawings to illustrate the environment and/or portions of the GRIPPING DEVICE FOR AN AVIONICS DISPLAY that form no part of the claimed design.
